UNITED STATES PATENT OFFICE.

MILTON HOERNER, OF HUMMELSTOWN, PENNSYLVANIA.

RECODER.

Application filed February 8, 1922. Serial No. 534,894.

To all whom it may concern:

Be it known that MILTON HOERNER, a citizen of the United States, residing at Hummelstown, in the county of Dauphin and State of Pennsylvania, has invented certain new and useful Improvements in Recorders, of which the following is a specification.

This invention has relation to certain new and useful improvements in a register and is especially designed for registering the number of boxes nailed by a nailing machine.

The invention has for its primary object the provision of a register which will be of comparatively simple and inexpensive construction and operation as well as highly efficient in use and which may be connected in any suitable manner to a nailing machine or the like for registering the number of boxes nailed or the articles passing through the machine.

The invention has for another object the provision of a register of the character set forth in which the parts will be constructed and arranged so that it may be readily determined by observing the register whether the machine to which the register is connected is operating regularly and rapidly enough to keep up with the work which must be fed to the machine.

The invention has for another object the provision of a register of the character stated in which is included mechanism for registering each box nailed and for indicating in series of fifty or more the number of boxes nailed by the machine, the indicating members being within view of the attendant, the register also including audible signalling means which may be operated automatically by operation of the register so as to notify the attendant that the machine is operating properly and the recorder taking note of the boxes nailed, the register being controlled by a movable member of the nailing machine, which operates once for each complete operation of the nailing machine.

A further object of the invention resides in the provision of a register of the character stated in which not only the number carrying wheels are operated but in which may also be included a member to be perforated on each complete rotation of the primary number carrying wheel so as to

form a permanent record of the number of boxes nailed by the machine to which the register is connected, this perforated member being removed after the total number of boxes are recorded by the register or at the end of the days work and a new recording disc placed in the register.

The invention has for a still further object the provision of a register of the character set forth which may be connected in any one of a number of different manners to the machine and which will be accurate in its operation of recording or registering the operations of the machine.

With the foregoing and other objects in view as will appear as the description proceeds, the invention consists in the novel construction, combination and arrangement of cooperating elements as hereinafter more specifically set forth, claimed and shown in the accompanying drawings forming a part of the present application and in which:

Figure 1 is a front elevation of the complete recorder.

Figure 2 is a vertical section through the recorder with the parts in normal position.

Figure 3 is a vertical transverse section through the recorder, at a right angle to Fig. 2 and taken substantially on the plane of line 3—3 of Fig. 2.

Figure 4 is a transverse section on the plane of line 4—4 of Fig. 2, looking in the direction indicated by the arrows.

Figure 5 is a detail transverse section substantially on the plane of line 5—5 of Fig. 3, looking in the direction indicated by the arrows.

Figure 6 is an enlarged detail sectional view substantially on the plane of line 6—6 of Fig. 2, looking in the direction indicated by the arrows.

Figure 7 is an enlarged detail section substantially on the plane of line 7—7 of Fig. 2, looking in the direction indicated by the arrows.

Figure 8 is a detail view of one of the rotatable members of the register, removed.

Figure 9 is a detail view of the recording disc and the parts between which this disc is to be mounted, these parts being removed.

Figure 10 is a detail view of one form of driving connection between the movable part of the nailing machine and the main operating member of the register.

Referring more in detail to the drawing

in which similar reference characters designate corresponding parts throughout the several views, 1 indicates the casing of the register and which may serve to enclose the operative parts of the machine, as will be evident by referring to the drawings. The register includes a reciprocating operating arm 2 working through a slot 3 in the casing 1 and connected in a suitable manner to an operative part of the machine with which the register is to cooperate. This arm 2 is to be connected in any suitable and well known manner, as may be later more fully described, so that upon each operation of the machine, the arm 2 may be reciprocated to cause operation of the register, as will be later clearly apparent.

Carried in the end of the arm 2 extending into the casing 1 is a stub-shaft 4, from which depends an arm 5 having a socket or eye 6 at its lower end and within which is secured one end of the main operating pawl 7 of the register, said pawl being secured in adjusted position within the eye or socket 6 by a set screw 8 or other suitable means. The free or working end 9 of the pawl 7 engages the peripheral teeth of the main ratchet wheel 10, as shown clearly in Fig. 2 of the drawings. This pawl 7 works through a guide member 11 mounted in the casing 1 and the working end 9 of the pawl 7 is resiliently retained in engagement with the teeth of the ratchet wheel 10 by a spring 12 or the like bearing upon the working end 9 of the pawl 7, as shown in Fig. 2. The spring 12 is shown as being mounted on a suitable support 13 carried in the casing 1. This may also be readily seen by referring to Fig. 2 of the drawings.

The ratchet wheel 10 is mounted on a suitable shaft 14 supported in the casing 1, preferably in the rear side thereof, as shown in Figs. 2 and 3 and the ratchet wheel 10 is secured upon the shaft 14 for free rotation thereon, a suitable nut 15 being mounted on the outer end of the shaft 14 and secured by a pivotal member such as the cotter pin 16 disclosed in Fig. 2, thereby making it impossible for the ratchet wheel 10 to work off of the shaft 14. This ratchet wheel 10 has an outstanding annular flange 17 formed on one face and provided with squares 18 upon its outer edge portion provided by markings on this edge portion and providing numbers in chronological order within the squares 18 so that these numbers may be brought one at a time before a sight opening 19 in the front face of the casing 1 and near the upper end thereof, as shown in the drawings, particularly Figs. 1 and 3. It may also be noted that the ratchet wheel 10 has a substantial hub portion 10' mounted on the shaft 14 so that the wheel 10 may be properly supported on the shaft and prevented from rocking thereon. In order to

prevent a reverse rotation of the ratchet wheel 10 a locking spring pawl 20, shown as being in the form of a leaf spring, is employed. One end of this locking pawl 20 is secured to the inner face of one side or edge portion of the casing 1, while the main portion of the locking pawl 20 is extended at an angle and engaged with the peripheral teeth of the ratchet wheel 10, as shown clearly in Fig. 2. The ratchet wheel 10 also carries a radially extending operating arm 21 suitably placed on the ratchet wheel 10 and projecting for some distance past the teeth of said ratchet wheel 10. This operating arm 21 carries an operating pin 22 in its outer end portion and extended laterally therefrom. The purpose of this pin 22 will presently appear. By referring to Fig. 3 of the drawings, it will be seen that a suitable spacing member 23 is mounted on the stub-shaft 14 to space the ratchet wheel 10 the proper distance from the wall of the casing 1.

Mounted on a suitable stub-shaft 24 positioned beneath and preferably to one side of the shaft 14, is an operating wheel 25. This wheel 25 is in the form of a disc and having laterally extending pins 26 projecting from its forward face, said pins 23 being suitably spaced around the edge portion of the wheel or disc 25, as shown clearly in the drawings. This wheel or disc 25 is properly spaced from the rear wall of the casing 1 by suitable spacing members 27 carried on the shaft 24. A bevel gear 28 is also carried on the front face of the wheel or disc 25 and the diameter of this bevel gear 28 is considerably less than the diameter of the wheel or disc 25, as will be clear from reference to Fig. 6 of the drawings as well as Fig. 3. Suitable nuts 29 or other members are secured on the outer or forward end of the shaft 24 to retain the wheel or disc 25 and its bevel gear 28 in proper position upon the shaft 24. The wheel or disc 25 together with its bevel gear 28 are adapted to be rotated one step on each complete revolution of the ratchet wheel 10, by engagement of the operating arm 21 with one of the pins 26 of the wheel or disc 25, as will be clear from referring to Fig. 2 of the drawings. As the wheel or disc 25 is rotated the bevel gear 28 will cause a limited rotation of the bevel gear 30 engaged therewith. This bevel gear 30 is mounted on a vertical shaft 31 carried in a suitable bearing 32 on the upper end of an upstanding post 33 secured in the bottom of the casing 1, as shown in the drawings. This bevel gear 30 has a plate or disc 34 mounted on its upper face and provided with suitable perforations, over which may be placed the numbers on one face of a recording disc 35 of paper or the like when the disc 35 is properly placed on the disc 34. The disc

35 may be held in proper engagement with the disc 34 by a plate 36 resting thereon and secured on the upper reduced extremity 37 of the shaft 31 by a thumb screw or the like, 5 as shown in Fig. 6 of the drawings. The recording disc 35 is adapted to be perforated at proper times by the perforating finger 39 adapted to reciprocate above the discs 34 and 35 and carried on the spring 10 arm 40. The pin 39 depends from the free end of the spring arm 40 which serves to normally force the perforating finger 39 downwardly to the recording disc 35, as will be later clearly apparent. The spring 15 arm 40 is mounted by its opposite end on a suitable supporting bracket arm 41 projecting from one wall of the casing 1, as shown clearly in Figs. 2 and 6 of the drawings. A lifting plate 42 is secured by one end to the 20 free end of the spring arm 40 and on the upper face thereof. This lifting member 42 is curved upwardly and one longitudinal edge projects beyond the corresponding longitudinal edge of the spring arm 40, said 25 member 42 being connected with the upper face of said spring arm 40, as shown clearly in Fig. 2 of the drawings. It is evident from this structure that the pin 22 carried by the operating arm 21 will ride under the 30 projecting longitudinal edge of the lifting member 42 and gradually raise the perforating finger 39 as the arm 21 moves toward the pin 26 which this arm is to engage on each revolution of the ratchet wheel 10. 35 This will release the gear wheel 30 as well as the bevel gear 28 and the disc or wheel 25 so that these parts may be operated by the operating arm 21 to cause a limited rotation of all of these parts, according to the 40 adjustment thereof. As the pin 22 leaves the lifting member 42 and the arm 21 is carried around away from the pin 26 with which it has engaged, the spring arm 40 will immediately serve to return the perforating finger 39 to its lowermost position and thereby permit this finger to pass 45 through the next number of the recording disc 35 brought to position under the perforating finger 39 and after which the perforating finger 39 will drop into the perforation in the disc 34 beneath this number. This will serve to securely lock all of the 50 wheels 30, 28 and 35 against further movement until the perforating finger 39 is again raised by the pin 22 on the next complete rotation of the ratchet wheel 10.

The bevel gear 30 also serves to drive the bevel gear wheel 43 mounted on a suitable shaft 44 carried in the forward portion 45 of a bracket arm 46 projecting forwardly from the bearing member 32, as shown clearly in Fig. 6 of the drawings. Suitable spacing washers 47 are mounted on the shaft 44 on either side of the bevel gear 43 and a lock nut 48 or other suitable means

may be mounted on the forward free end of the shaft 44 to retain the bevel gear wheel 43 in proper position thereon and in engagement with the bevel gear 30. It is to be seen that the shaft 44 is in a horizontal 70 plane below the plane of the shaft 24 and forwardly thereof. This bevel gear 43 has an outstanding angular flange 49 on its front face with its outer edge marked off into squares 50 with numbers arranged in 75 chronological order in said squares 50 so that they may be brought one at a time before a sight opening 51 in the lower portion of the front face of the casing 1, as shown in Figs. 1, 3, and 6. These numbers are 80 preferably arranged so as to show the total number of operations of the register and thereby indicate the number of boxes nailed when this device is connected with a nailing machine. It is therefore evident that if fifty 85 numerals appear on the flange 17 of the ratchet wheel 10, the numbers in the blocks or squares 50 on the flange 49 of the bevel gear 43 should be arranged in series of fifty, that is beginning with fifty, one hundred, 90 one hundred fifty, two hundred, etc., as this bevel gear wheel 43 is rotated only one space or one block on each complete revolution of the ratchet wheel 10, while the ratchet wheel 10 is rotated one number on 95 each operation of the machine controlling the action of the arm 2 for operating the register.

In order that an audible signal may be given when the bevel gear 43 has made its complete revolution to bring the highest number appearing on the flange 49 thereof in front of the sight opening 51 of the casing 1, a laterally extended pin 52 which may be called a circuit closing pin is carried by the gear wheel 43 and extended outwardly from one face thereof and laterally from the same, near the edge of the front face of the bevel gear 43. This pin 52 is adapted to ride over the curved free end 53 of the member 54 and press this free curved end 53 of the member 54 onto the second spring contact member 55, above which this end 53 of the member 54 is normally spaced. The spring contact members 53 and 54 are mounted on suitable supports 56 and have electrical connection with the current conducting wires 57 leading to opposite poles of a battery 58 or other source of electric energy within the casing as shown in Fig. 2 or outside of this casing. A switch member 59 is shown in one of the current conducting wires 57 and adapted for engagement with the switch point 60 so that a circuit may be completed through the current conducting wires 57 and through the audible signal 61 in the path of one of said wires 57 when the contact members 54 and 55 are engaged by movement of the pin over the end 53 of the contact member 54, as stated. It is therefore evident that the attend- 120

ant may have proper notice when the highest number of the register has appeared before the opening 51. This will give the attendant a chance to open the enlarged or widened lower portion of the casing 1 and remove the perforated disc 35 and substitute therefor a new recording disc, as it may be desired. It is also evident that the casing 1 may be readily opened and any of the parts 10 of the register inspected, repaired or replaced, as desired.

While the operating arm 2 of the register may be connected in any suitable manner to the nailing machine bar or some other operative part of the nailing machine or other machine to which this register is to be connected, I have shown a novel form of connection in Fig. 10. By referring to this figure of the drawings, it will be seen that 15 the operating arm 2 is pivotally connected at one end, as shown at 62 to a curved arcuate member 63 having one end pivotally mounted, as shown at 64, either to the framework of the nailing machine or to some 20 other stationary support. The opposite end of the curved or arcuate spring member 63, however, is pivotally connected as shown at 65 to the nailing machine bar 66 whereby reciprocation of this nailing machine bar 66 25 will cause movement of the curved or arcuate spring bar 63 as indicated by dotted lines in Fig. 10, thereby resulting in a reciprocation of the operating arm 2 of the register. By such a connection, the register may be 30 spaced a suitable distance from the nailing machine so as to be out of way of the operative parts of the nailing machine, thus preventing interference of the register with the nailing machine. It is evident that the connection of the register with the nailing machine or other machinery with which the register is to be employed may be varied as 35 desired or as the occasion may require.

It is believed that the complete construction and operation of this register may now be apparent without further detailed description. It may be briefly stated, however, that upon each reciprocation of the operating arm 2 which should correspond with 40 each operation of the machine to which the register is connected, the ratchet wheel 10 will be operated by the pawl 7 one or more notches as may be required to cause a sufficient rotation of the wheel 10 to bring the 45 next number in order on the flange 17 thereof before the sight opening 19 in the front of the casing 1 and located in the upper portion of said casing 1. Each complete rotation of the ratchet wheel 10 will result in rotation 50 of the wheel or disc 25 as previously stated. This rotation of the wheel or disc 25 occurs after raising of the perforating finger 39 and resulting in rotation of the bevel gear 30 and the bevel gear 43 to bring the next 55 number in order on the flange 49 of the bevel

gear 43 before the lower sight opening 51. When the bevel gear wheel 43 has made its complete revolution to bring the highest number on the flange 49 thereof before the lower sight opening 51, the audible signal is given by a forced engagement of the contact members 54 and 55, as more specifically set forth in the foregoing paragraphs.

It is believed the complete operation of the register may now be readily understood 75 without further description thereof.

While the preferred embodiment of the invention has been shown and described, it is to be understood that minor changes in the details of construction and arrangement 80 of parts may be resorted to within the scope of what is claimed without departing from the spirit of the invention.

What I claim is:

1. A registering device of the class described including a casing, a primary registering wheel rotatably mounted therein, a secondary registering wheel rotatably mounted in said casing, a recording disc carried on said secondary wheel, means for perforating said disc and simultaneously locking said secondary wheel against rotation, and means actuated by the primary registering wheel at predetermined time adapted to actuate the last mentioned means for rotating said secondary wheel and further perforating said disc.

2. A registering device of the class described including a casing, a primary registering wheel rotatably mounted therein, a secondary registering wheel rotatably mounted in said casing, a recording disc carried on said secondary wheel, a spring supported pin adapted to perforate said disc and simultaneously lock said secondary registering wheel against rotation, and means actuated by the rotation of said primary wheel to operate said pin and cause rotation of said secondary wheel.

3. A registering device of the class described including a casing, a primary registering wheel rotatably mounted therein, a secondary registering wheel rotatably mounted in said casing, a recording disc carried on said secondary wheel, means for perforating said disc and simultaneously locking said secondary registering wheel against rotation and an intermediate rotary element for actuating the perforating means and rotating said secondary wheel.

4. A registering device of the class described including a casing, a primary registering wheel rotatably mounted therein, a secondary registering wheel rotatably mounted in said casing, a recording disc carried on said secondary wheel, a spring supported reciprocating pin adapted to perforate said disc and simultaneously lock said secondary wheel against rotation, and means adapted for engagement with the spring support of

said reciprocating pin to release the latter from its engagement with said disc and simultaneously rotate said secondary wheel.

5. A registering device of the class described including a casing, a primary registering wheel rotatably mounted therein, a secondary registering wheel rotatably mounted in said casing, a recording disc carried on said secondary wheel, a spring supported reciprocating pin adapted to be positioned normally to perforate said disc and simultaneously lock said secondary wheel against rotation, and a rotary element within said casing having means thereon for releasing said pin from its perforating and locking position and simultaneously rotating said secondary wheel.

6. The combination with a registering mechanism including a rotary element, a projecting element carried thereby, a rotary disc, a plurality of lateral fingers carried thereby to be engaged by the projecting element to move the disc step by step, a normally stationary gear supported adjacent the disc, a recording sheet supported on the upper face thereof and provided with indicia, and a spring-urged pin adapted to perforate the sheet and hold the gear stationary, the pin being disengaged from the gear and sheet by the projecting element.

7. The combination with a registering mechanism including a rotary element, a projecting element carried thereby, a rotary disc, a plurality of lateral fingers carried thereby to be engaged by the projecting ele-

ment to move the disc step by step, a normally stationary gear supported adjacent the disc, a recording sheet supported on the upper face thereof and provided with indicia, a spring-urged pin adapted to perforate the sheet and hold the gear stationary, the pin being disengaged from the gear and sheet by the projecting element, and an element operated by the gear and provided with indicia for indicating the revolutions of the gear.

8. In a registering device, the combination with a rotatable element actuated step by step by a movable part of a machine, a gear, a recording sheet secured to the upper face thereof, a reciprocating element adapted to perforate the recording sheet and normally hold the gear stationary, a resilient arm to which the reciprocating element is attached, cooperating means between the rotary element and resilient arms for disengaging the reciprocating element from the gear and recording sheet.

9. The combination with a rotary element rotatable step by step by a movable part of a machine, a rotary member arranged below the same, a recording sheet mounted on the rotary member and coacting means between the rotary element and rotating member providing a driving connection for the latter and simultaneously perforating the recording sheet, such means being operable at predetermined intervals.

In testimony whereof I affix my signature.

MILTON HOERNER.
